UNITED STATES PATENT OFFICE.

ADOLPH F. CHRISTMAS, OF EASTON, PENNSYLVANIA, ASSIGNEE TO INGERSOLL-RAND COMPANY, OF JERSEY CITY, NEW JERSEY, A CORPORATION OF NEW JERSEY.

GOVERNING MECHANISM FOR INTERNAL-COMBUSTION ENGINES.

1,349,146.

Specification of Letters Patent. Patented Aug. 10, 1920.

Application filed May 26, 1915. Serial No. 30,508.

To all whom it may concern:

Be it known that I, ADOLPH F. CHRISTMAS, a citizen of the United States, residing at Easton, in the county of Northampton and State of Pennsylvania, have invented a certain new and useful Improvement in Governing Mechanism for Internal-Combustion Engines, of which the following is a specification.

10 This invention relates to governors for oil engines, and more particularly to governors for oil engines of the type wherein the cylinder head is maintained at a substantially constant temperature and fuel is sprayed in and ignited by the combined heat of the head and the compressed air charge near the top of the piston stroke. When oil engines of this type are operated through a considerable range of loads 20 I have found that the regulation is affected considerably by the fact that when a very small amount of fuel is injected into the charge of air compressed by the up-stroke of the piston the ignition of the resulting 25 combustible mixture is somewhat delayed, owing, probably, to the fact that the particles of fuel are somewhat separated and the combustion is more slowly propagated through the mixture than when a greater 30 amount of fuel is present. This results in an ineffective use of the fuel under light load conditions as it is evident that if the fuel is injected at the same point in the stroke under all load conditions the delay 35 in complete ignition at low loads will cause the greatest combustion pressure under such loads to be developed at an ineffective point in the piston stroke, this discrepancy being the more marked due to the fact that under 40 the lightest loads the engine is running at the highest speeds.

To overcome this disadvantage I have conceived the idea of injecting the fuel at progressively earlier points at the piston stroke as the load becomes lighter, the fuel thus having a chance to become completely ignited at the proper point of the piston stroke under all load conditions.

To accomplish this result I have devised 50 a governing mechanism, a practical embodiment of which is represented in the accompanying drawings, in which—

Figure 1 shows a side elevation of an oil engine provided with my governing mechanism, and

Fig. 2 is a diagram showing the operation of the governor under various load conditions.

In the drawings is shown the cylinder 1 of an oil engine of the type shown, for instance, in my copending application Serial No. 860,481, filed September 5th, nineteen hundred and fourteen. The fuel is injected into the head of this cylinder 1 on every piston stroke through a nozzle 2 from a pump 3 which comprises a cylinder 4 and a plunger 5, fuel being admitted from a supply, not shown, by a valve 6 and discharged through a similar valve 7 and a pipe 8 to the nozzle 2. The plunger 5 is operated in a direction 60 to draw fuel into the cylinder 4 by means of a spring 9. Its discharge stroke is effected by a striking arm 10 which is operated by a connecting rod 11, driven from the governing mechanism which is secured to the fly 70 wheel 12 of the engine. This connecting rod 11 or plunger operating rod is pivotally secured to a controlling lever 13, one end of which is pivoted on a pin 14 on the hub of the fly wheel 12 eccentrically of the axis 80 thereof, and the other end of which is connected by a link 15 to a governor weight 16 which is pivoted at 17 on a spoke of the fly wheel and moves outwardly against the tension of the spring 18 as the speed of the engine increases, these parts being so arranged 85 that as the speed of the engine increases, the pivot point of the connecting rod 11 on the lever 13, which at all times is eccentric of the fly wheel axis, moves inwardly toward 90 said axis and at the same time forwardly in the direction of rotation of the fly wheel. This movement can be more readily understood by referring to Fig. 2.

In the diagram, the dotted line O P W 95 represents the position of the lever 13 when the engine is running at full load, and hence at its slowest speed. When the lever 13 is in this position the connecting rod 11 is at the center of its forward or pumping stroke, 100 its pivot point P on the lever 13 being directly below the axis C of the fly wheel 12. In this position of the lever, which is that shown in Fig. 1, the striking arm 10 will not be in operative contact with the plunger 105 5, such an operative contact not being established until the lever reaches the position shown in the full lines O² P² W². The striking arm 10 will then be in the position shown in Fig. 2, and further travel of the 110

connecting rod 11 will cause a forward movement of the plunger 5 and consequently fuel injection until the pivot point of the rod 11 on lever 13 reaches the farthest point 5 of its forward stroke on the line D—D. From this description it will be evident that when the engine is operating under its highest load and at its lowest speed, the pivot point P of the connecting rod 11 will move 10 in a circle having the radius C P, the latter part of the forward travel of the connecting rod 11 causing an injection of fuel into the engine cylinder. Now, supposing the engine to be operating at its lightest load, and consequently 15 its greatest speed, and the pivot point O of the lever 13 on the hub of the fly wheel to be in the same position as in the case first considered, the positions of the points P and W will be greatly altered 20 by the outward movement of the weight 16, the point W moving upward a considerable distance to the point W^1 , while the point P will move to the point P^1 , which is not only closer to the axis C of the fly wheel, but is, 25 say, 90° farther advanced in the direction of rotation of the fly wheel than the point P. This change of position will not only result in a shortening of the stroke of the pump plunger, but will cause this plunger 30 stroke to occur much earlier in the stroke of the engine. This is apparent by considering the position of the lever 13 when the stroke of the plunger 5 commences under these light load conditions, which is shown 35 by the line $O^3 P^3 W^3$, it being evident that in this position the striking arm 10 engages the plunger 5 ninety degrees earlier in the revolution of the fly wheel than when the lever 13 is in its highest load position shown by $O^2 P^2 W^2$, while at the same time 40 the effective stroke of the plunger is only a small part of that at the highest load since the pivot point of the connecting rod 11 is traveling in a circle with only a radius 45 C P^1 . In practice I have found that at full load the injection of the fuel may commence about forty degrees before the piston has reached the end of its compression stroke, whereas at light loads the commencement 50 of the injection may be sixty degrees to ninety degrees earlier in the stroke, time being thus given for complete combustion of the more widely separated fuel particles at an effective point in the piston stroke. 55 While my invention is primarily adapted for oil or internal combustion engines it may with advantage be applied to steam or other engines whose speed is to be maintained at as constant a rate as possible.

Should it be desired to utilize my invention 60 for steam or other elastic fluid engines the rod 11 which, in the modification selected for example in this application, is connected to a plunger oil pump, would be connected directly to a valve of any well known construction the movement of which would be controlled and consequently the amount of elastic fluid admitted to the cylinder would be varied according to the eccentricity of the 65 pin on the lever 13. 70

It is to be understood that while the present showing and description discloses only one specified modification of my invention, other forms and modifications are included in the spirit and scope of the same, as expressed 75 in the claims.

What I claim is:

1. In a fuel injector for oil engines, a fuel pump, a plunger therefor, a rotary element, a centrifugal element rotating with said rotary element, a controlling lever pivoted at one end eccentrically of said rotary element, a plunger operating rod pivotally secured to said controlling lever between the said pivot point of said lever and the rotation center of the rotary element and a connection between the other end of said controlling lever and said centrifugal element adapted to rotate said controlling lever oppositely to the direction of rotation of said rotary element and advance the point of connection between the plunger operating rod and the controlling lever in the direction of rotation when the speed increases, said movement serving to actuate said plunger 90 earlier in the piston stroke of said engine, the movement of said plunger being derived solely from said controlling lever. 95

2. In a fuel injector for oil engines, a fuel pump, a plunger therefor, a fly wheel, a controlling lever pivoted at one end eccentrically of said fly wheel center, a plunger operating rod secured to said controlling lever between the said pivot point of said lever and the fly wheel center, a centrifugal element, and a connection between said centrifugal element and the other end of said lever for rotating said controlling lever oppositely to the direction of rotation of the fly wheel and advance the point of connection between the plunger operating rod and the controlling lever in the direction of rotation when the speed increases, movement of said plunger being derived solely from 100 said controlling lever. 105

In testimony whereof I have hereunto set my hand.

ADOLPH F. CHRISTMAS.
